United States Patent Office.

BINDLOSS H. HILLIAR, OF NEW LONDON, CONNECTICUT.

Letters Patent No. 103,182, dated May 17, 1870.

IMPROVED ICE-CREAM FREEZER.

The Schedule referred to in these Letters Patent and making part of the same.

To all whom it may concern:

Be it known that I, BINDLOSS H. HILLIAR, of the city and county of New London, and State of Connecticut, have invented a new and useful Improvement in Ice-cream Freezers; and I do hereby declare the following to be a full, clear, and exact description of the same, reference being had to the accompanying drawing making part of this specification, in which—

Figure 1 is a plan.

Figure 2 is in part a vertical section, and part an elevation, of my improved apparatus.

Figure 3 is a section of the end of the arm *g*, showing the rubber springs and their connection with the arm and dashers.

Figure 4 is a top view of the same.

Figure 5 is a top view of the sleeve and socket which works the cream-can, and its connection with the crank, and also shows the stationary pinions which prevent the dasher from turning.

Figure 6 is a vertical section of the same.

The same marks of reference indicate similar parts in each figure.

The nature of my improvement consists in the construction, arrangement, and operation of the several parts, hereinafter fully shown and described.

In the drawing—

a and *a'* represent the ice-cans, resting upon the bed *b*, or they may rest upon the floor, table, or other convenient place.

c are the cream-cans, supported by a step-bearing at the lower end at *j*, and at the upper end by the bearing *k*.

This bearing is attached to the cover *e*, as shown in fig. 2, and its outside is square, and fits into the socket *2*, (see fig. 6.)

d is a vertical shaft, to which are attached the arms *g* *g*, which may be two or more in number on each shaft.

The upper end of this shaft is slotted, to receive the clutch *s* at the lower end of the pinion *s*.

e is the cover of the cream-cans, and is held in position by the pins and socket *e'*, so that, by turning the covers around, the cans are caused to turn.

f *f* are the dashers or scrapers, which scrape the cream from the inside surface of the cream-cans, as it becomes attached by freezing.

h *h* are rubber springs, placed in the recess back of the dashers, so that, if the ice becomes thick on the surface of the can, the dashers will spring back, but will press against the cream and scrape it off gradually.

l is the plate which connects and holds together the mechanism hereafter described.

m *m* are bosses cast on the ends of the plate *l*, and are bored to receive the sleeve *o*.

n *n* *n* are legs attached to the bottom of the plate *l*. Their lower ends are slotted, so as to fit the tops of the ice-cans, as shown in figs. 1 and 2.

o *o* are sleeves, running through the bosses *m* *m*.

The lower ends of these sleeves form the socket *2*, and the arms *p* are made fast to the upper ends, as shown in figs. 1, 5, and 6.

r is a ball or handle, for conveniently handling the plate.

This handle is secured to the upper end of the pinions *s*, so as to prevent their turning.

t is the driving-shaft, working in the bearings *t* *t*.

v *v* are bevel or miter-gears, one of which is attached to one end of the shaft *t*, the other being attached to the vertical shaft *x*, so as to gear together.

w is a crank or crank-wheel, attached to the upper end of the shaft *x*.

w' is the crank-pin.

z *z* are connecting-rods, by which motion is communicated from the crank-wheel *w* to the arms *p*.

y is a balance-wheel, by which the irregular motion of the machine is equalized.

The operation of my improvement is as follows:

The requisite amount of cream is placed in the cream-can *c*, and the cover *e* put on, as shown in fig. 2.

The annular space around the cream-can is filled with the freezing material, and the plate *l* properly placed in the position shown in figs. 1 and 2.

It will be seen that the square socket *2*, fitting the bearing *k*, the outside of which is also square, and the clutch *s*, fitting the slot in the upper end of the shaft *d*, and the other mechanism connected as shown and described, motion being communicated to the apparatus by turning the crank *3*, the bevel-gears *v* and the wheel or crank *w* will revolve, and, by means of the connecting-rods *z* *z*, cause the arms *p* to oscillate, turning the cream-cans partly around backward and forward, while the shaft *d*, the arms *g*, and dashers *f* are held stationary by the stationary pinion *s*.

In order to hasten the freezing, it is desirable to keep the frozen cream scraped clean from the inner surface of the cream-cans, and to allow the liquid portions to come in contact with said surface.

For this purpose the dashers *f* are adjusted, by means of the screws *i*, (shown only in figs. 3 and 4,) so as to fit the inner surface of the cans, while should there be any irregular surfaces on the cans

or should the layer of cream become thick by standing, the rubber springs will yield and allow the dashers to move back, so as to pass over such irregular surfaces, and to press against and scrape off such thick layers of cream gradually.

Fig. 2 is a view with the can-covers removed. The mechanism not fully shown in *a'* is the same as that in *a*, and any number of cans may be operated together, being connected by connecting-rods like *z* to arms like *p*.

What I claim as my invention, and desire to secure by Letters Patent, is—

The plate *t*, the connecting-rods *z z*, the arms *p*, the sleeve and socket *o* and *2*, the stationary pinion and clutch *s* and *s'*, the bail *r*, and legs *n*, the whole being constructed, arranged, and operated substantially as shown and described, and for the purpose specified.

New London, December 6, 1869.

BINDLOSS H. HILLIAR.
